J. Lewis
Printing Press.
Patented Jan. 2. 1855.

Nº 12185.

Patented Jan. 2, 1855.

UNITED STATES PATENT OFFICE.

JAMES LEWIS, OF PRATTVILLE, NEW YORK.

PRINTING-PRESS.

Specification of Letters Patent No. 12,185, dated January 2, 1855.

To all whom it may concern:

Be it known that I, JAMES LEWIS, of Prattville, in the county of Greene and State of New York, have invented a new and Improved Printing-Press; and I do hereby declare that the following is a full, clear, and exact description of the same, reference being had to the annexed drawings, making a part of this specification, in which—

10 Figure 1 is a side elevation of my improved printing press. Fig. 2 is a longitudinal vertical section of do. Fig. 3 is a detached plan or top view of the bed, ways, and case bar of the fly.

15 Similar letters of reference indicate corresponding parts in the several figures.

This invention relates to a new and improved printing press and consists 1st in the employment or use of a fly constructed 20 arranged and operating as will be hereafter shown, and 2nd in the combination of the fly, with the cylinder and bed plate of the press.

To enable others skilled in the art to make 25 and use my invention, I will proceed to describe its construction and operation.

A represents the frame of the press, having two uprights (a) (a) one at each side in which the axes (b) of a cylinder B has 30 its bearings. At each end of the cylinder B there are cogs or teeth (c) which extend half way around the cylinder see Figs. 1 and 2.

C is the bed of the press on which bed 35 the form from which the impressions are taken is placed. The bed C runs or works upon ways (d) (d) which are placed longitudinally on the upper part of the frame A. The ways are shown more particularly in 40 Fig. 3. At each side of the bed C there is a rack (e), both racks are shown in Fig. 3 and one in Figs. 1 and 2.

D, Figs. 1 and 2 represents the fly which is formed of two uprights (f) (f) attached 45 by pivots (g) (g) to the ends of a bar E which works or runs on the ways (d) (d). The base bar detached from the uprights is shown in Fig. 3. The upper ends of the uprights are connected by a horizontal bar or 50 cross piece F having lips (h) on its front end, see Figs. 1 and 2. Directly underneath this bar or cross piece F there is a bar G which is secured by pivots (i) at its ends to the upright (f) (f). At each end of the 55 bar G there is a small arm (j) to which a spring (k) is attached. The springs (k)

keep the edge of the bar G close against the lips on the bar or cross piece F. At the back of the bar G, at about its center, there is a rod (l) which projects outward a suitable distance as shown in Figs. 1 and 2.

60 The bar E to which the uprights (f) (f) are attached has horizontal bars (m) (m) secured one at each end, or near the ends, said bars rest on ledges or strips (n) (n) 65 by the side of the ways (d) (d) as clearly shown in Fig. 3. The ends of the bars (m) (m) have projections or hooks (o) (o) upon them as shown in Figs. 1 and 2 and by dotted lines in Fig. 3. And the inner end of 70 the bed C is provided with buttons (p) (p).

To one side of the uprights (a) (a) there are attached arms (g) (g) one to each, and at the upper ends of those arms are secured bent levers (r) (r) provided with springs 75 (t). At each end of the cylinder B there is a pin (u) the position of which is shown by dotted lines in Fig. 1. And there is attached to one of the uprights (a) a bent rod (v) shown in Fig. 1.

80 Across the face of the cylinder B there is a rod H having fingers (w) attached to it, see Fig. 2, one end of this rod is provided with a spring (not shown) which keeps the fingers down upon the cylinder. The opposite end of the rod is bent over at right angles as shown by the dotted lines (y) in Fig. 1.

I is a horizontal fly board attached to the back end of the frame A as shown in Figs. 90 1 and 2.

J, J, J, are the ink rollers arranged as usual and driven in any proper manner.

95 Operation: The form shown in red in Fig. 2 and indicated by (b') is placed upon the bed C. And the paper to be printed is placed upon a feed board indicated by (a') see dotted lines in Fig. 2. The cylinder B is then rotated and when the bent end (y) of the rod H comes in contact with the bent rod (v) attached to the upright (a), the fingers (w) on the rod H are raised upward from the cylinder B and the edge of the sheet of paper is slipped underneath them, the fingers falling upon the edge of the sheet 100 when the bent end (y) of the rod H has passed the bent rod (v), the sheet being thus attached to the cylinder B is carried around with it, and is pressed between the cylinder and the form shown in red and designated by (b') Fig. 2, the form being upon 105 the bed C, which is moved in the direction 110

of arrow 1 during the time the impression is given by the teeth or cogs (c) on the ends of the cylinder gearing into the racks (e) (e). When the fingers (w) get nearly to the 5 point at which they receive the sheet, the pins (u) at the ends of the cylinder B acts upon the bent levers (r) and the bar G is depressed, that is, its inner edge, and the edge of the printed sheet is caught between 10 the bar G and lips (h) of the bar F as shown in Fig. 2 the sheet being shown in red and indicated by (c') the buttons (p) (p) now come in contact with the bar E of the fly D and force it back till the lower ends of the 15 uprights (f) strike against pins (d') at the sides of the frame A, see Fig. 2 and the top part of the uprights (f) (f) are thrown back the rod (t) passing over a bar (e') on the fly board which causes the inner end of the 20 bar G to be depressed and the printed sheet falls upon the fly board I. At this time the cogs on teeth (c) on the cylinder B have just passed the racks (e) (e) on the bed C and the bed C and the fly D are brought back to

their original position by a weight K which 25 is attached to the bed by a cord A'

The above press is extremely simple and will work with great rapidity and with a small expenditure of power. They can be made at a small cost and are not liable to 30 get out of repair.

Having thus described my invention, what I claim as new and desire to secure by Letters Patent, is,

1. The employment or use of the fly D 35 constructed arranged and operating in the manner and for the purpose as herein set forth.

2. I claim the combination of the fly D, cylinder B and bed C, when the above parts 40 are arranged operated as herein shown and described.

JAMES LEWIS.
